UNITED STATES PATENT OFFICE.

CARL KRAFT, OF NEW YORK, N. Y.

ELECTRICAL CONNECTING PLUG.

Application filed June 8, 1922. Serial No. 566,260.

To all whom it may concern:

Be it known that I, CARL KRAFT, a citizen of the United States, and a resident of the county, city, and State of New York, have invented certain new and useful Improvements in Electrical Connecting Plugs, the complete specification of which is as follows.

The plug to which my invention particularly relates is the two conductor plug commonly used in establishing electrical connection in communicating systems of all kinds.

Plugs of this type are common but my invention discloses two features, separate and distinct from all plugs used at present. First, I have invented a plug involving nothing other than so called "screw-machine" parts. Secondly, I have added an adjustable feature enabling the user to adjust the plug to suit the individual jack. The second feature is quite important for I have found that regardless of the make of jack, irregularities present themselves.

I have appended an illustrative sheet showing two preferred embodiments of my invention. In these figures like designations refer to like parts.

Fig. 1 shows a full sectional elevation of one type of my plug connector in its simplest form.

Fig. 2 shows an elevation of the same plug.

Fig. 3 shows a section of the same type of plug with the feature of the adjustable sleeve added.

In Figure 1, A represents an insulated cylindrical handle having an orifice B capable of accommodating the connecting wire used in these devices. The metallic body K is a solid of revolution, as is the handle. The body K constitutes what is commercially and technically known as the sleeve of the plug. The sleeve is one of the connecting surfaces. The sleeve K is in threaded contact with the handle A, as shown. The inner diameter of the sleeve K contains an insulating cylinder M, having a shoulder butting against the inner face of the sleeve. The shoulder may be omitted since I find the plug operates without the shoulder if the cylinder M fits properly. The insulating washer N may in some cases be included as an integral part of insulating cylinder M. The so called tip connection is made by tip P, in threaded contact with rod O, which rod is an integral part of the disc H. The

disc H is metallic and is drilled to hold the binding post D. The binding post D is drilled to provide a cord binding orifice G, so that tension on the connecting wires will not injure the electrical connections. The sleeve contact binding post E is insulated from the disc H by the insulating sleeve I but is in threaded engagement with the sleeve face at J. The set screws F are provided in the binding posts so that all electrical connections may be secured.

In Fig. 2, like figures refer to like parts. The arrangement is obvious and shows the plug in external appearance.

In Fig. 3, A represents the insulating handle, K the sleeve and R a lock screw arrangement for adjusting the distance from the surface S to the tip of the plug. The adjustment is made to accommodate the plug to the jack with which the plug is used. Then the handle A is screwed down locking the adjustment by pressure at T. The surface R may be knurled if desired.

In Fig. 1, in place of the small shoulder L a knurled shoulder may be used but I have not included this in the illustration because the plug shown is the simplest type.

It is to be noticed that each and every part of my device may be readily made on a "screw-machine." That is, bodies A, H, D, F, E, M, N, K, and P are essentially solids of revolution and not stampings or castings. This fact is one of the salient features of my invention since it greatly facilitates rapid and inexpensive manufacture. The second feature of my invention which I have just disclosed is the adjustable sleeve length.

Having thus described my invention, what I claim and what I desire to secure United States Letters Patent for is:

A two conductor electrical plug connector composed entirely of screw machine parts, the parts constituting a main insulating handle and an assembled plug connection, said handle being a solid of revolution known as a screw machine product, and being so turned as to accommodate the connecting wires in one end and the electrical plug assembly in the other, which electrical plug assembly is in part composed of a threaded sleeve contact connection engaging the said insulating handle, which contact sleeve is a solid of revolution and drilled to accommodate an insulating cylindrical sleeve, which insulating sleeve is so con-

structed as to reach from the extreme outer end of the contact sleeve in front to a point a short distance behind the rear face of the contact sleeve, in the orifice of which insulating sleeve is a metallic screw machine product constituting part of the tip connection, which consists of a flat cylindrical disc, a shaft integral with said disc, the disc being drilled in one location to receive a binding post connection and drilled in another to accommodate an insulating bushing while the shaft is threaded to accommodate the metallic tip and an insulating washer, said flat cylindrical disc supporting a metallic binding post into which binding post is drilled one orifice for accommodating the connecting wires and a second orifice for accommodating a holding cord, the first orifice

being provided with a set screw, both binding post and set screw being screw machine parts, in the second opening in said flat cylindrical disc there being an insulating bushing and a binding post screwed into the metallic sleeve connection, both binding post and bushing being screw machine products, over which sleeve connection is provided a locking arrangement for adjusting the distance from the end of the sleeve to the shoulder of said sleeve. 20 25

In witness whereof I hereunto subscribe 30 my name this 5th day of June, 1922.

CARL KRAFT.
